UNITED STATES PATENT OFFICE.

GEORGE HENRY WHEARY, OF RACINE, WISCONSIN, ASSIGNOR TO WHEARY-BURGE TRUNK COMPANY, OF RACINE, WISCONSIN, A CORPORATION OF WISCONSIN.

CURTAIN AND LAUNDRY BAG.

Application filed September 24, 1921. Serial No. 502,968.

To all whom it may concern:

Be it known that I, GEORGE HENRY WHEARY, a citizen of the United States, and resident of Racine, in the county of Racine 5 and State of Wisconsin, have invented new and useful Improvements in Curtains and Laundry Bags, of which the following is a description, reference being had to the accompanying drawings, which are a part of this specification.

This invention relates to the improvements in curtain and laundry bags more particularly adapted for wardrobe trunks.

In ordinary wardrobe trunks garments are 15 draped on hangers which are suspended in the upper portion of the wardrobe section of the trunk and the lower portion of said section usually carries a shoe box. A hinged cover is provided for the upper portion of 20 said wardrobe section to permit convenient access to the suspended garments.

It is one of the objects of the present invention to provide a curtain and laundry bag which may be easily mounted within the 25 wardrobe section to cover the open front and top thereof.

A further object of the invention is to provide a curtain and laundry bag which will extend over the front and top portion of a 30 wardrobe section to protect the garments therein and which will also hold soiled linen and keep it separate from other articles of wear.

A further object of the invention is to 35 provide a combination trunk section cover and laundry bag which is adapted to maintain garments suspended within the wardrobe section of the trunk in position on the hangers.

A further object of the invention is to 40 provide a trunk laundry bag and cover in which parts may be easily detached from the trunk to permit access to the garments or the cover may be entirely removed from the trunk for 45 cleaning.

A further object of the invention is to 50 provide a curtain and laundry bag which is of simple construction, is strong and durable, and is well adapted for the purpose de-

With the above and other objects in view the invention consists of the improved curtain and laundry bag and its parts and combinations as set forth in the claims, and all equivalents thereof.

In the accompanying drawings in which the same reference characters indicate the same parts in all of the views:

Fig. 1 is a front view of the wardrobe section of a wardrobe trunk showing the improved curtain and laundry bag mounted therein, a part shown as broken away, the view also showing a portion of the other section of the trunk;

Fig. 2 is a vertical sectional view thereof 65 taken on line 2—2 of Fig. 1;

Fig. 3 is a sectional detail view of the rod, on a larger scale, for connecting the rear edge portion of the curtain to the wardrobe section, the view also showing portions of the 70 trunk section; and

Fig. 4 is a similar view of the lower connecting member of the cover.

Referring to the drawing the numeral 5 indicates the wardrobe section of a wardrobe 75 trunk and 6 the drawer section hinged thereto. The wardrobe section is also formed with an open top 7 provided with a hinged cover 8. The wardrobe section is provided with upper parallel fixed tracks 9, hinged extension tracks 10, garment hangers 11 slidably mounted on the tracks and a swingable shoe box 12 mounted in the lower front portion of the wardrobe section.

The improved curtain and laundry bag 13 85 comprises a piece of material, such as fabric, which extends horizontally from the upper rear portion of the wardrobe section of the trunk over the garment hangers and the extension tracks and then downwardly in front of the wardrobe section and terminating in front of the upper edge portion of the shoe box. The upper rear edge portion of the fabric is in the form of a loop 14 for removably receiving a rear connecting bar 15 95 which is formed with reduced end portions 15' and 16 adapted to enter openings 17 in the collar 18 of the wardrobe section. The reduced end portion 16 of the bar 15 is in the form of a plunger which is slidably 100

mounted in the tubular end portion of the bar and is yieldingly urged outwardly by a coiled spring 19 positioned in said tubular end portion. In removing the bar it is only necessary to push the reduced end portion 16 inwardly to clear the side portion of the collar and the end of the bar may then be swung upwardly and the other end withdrawn endwise from the other side of the collar.

The vertically extending portion 13' of the fabric is of double thickness with the inner portion of considerable fullness to form a laundry bag 20, access to which is through the opening 21 closed in any manner desired but preferably by a slidably locking member 22 also of ordinary construction.

By positioning the laundry bag portion in the lower front portion of the wardrobe section, space is utilized which is not ordinarily used and as garments are removed from the hangers and the space is gradually, automatically increased inwardly for holding the soiled apparel.

The lower end portion of the fabric is also formed with a loop 23 to receive the lower securing bar 24 which is adapted to enter the openings 24' of brackets 25 mounted on the inner side of the trunk section angled valance or frame 26 of the trunk. The extension portion 27 of the bar 24 which enters one of the brackets 25 is of tubular construction and telescopes over the reduced end portion 24' of said bar 24. A coiled spring 28 positioned within the bore of the extension bar end and between the ends of said extension and said bar removably holds the lower portion of the curtain connected to the valance of the trunk. To release the lower portion of the curtain it is only necessary to grasp the bar 24 at any point and push it a slight distance towards the extension end to disengage the other end from the valance and tilt the free end and then move the bar endwise to disengage the extension end from the other part of the valance. This construction also permits the easy removal of the bars from the fabric so that said fabric can be easily cleaned.

As the fabric extends over the open top and front open side portion of the wardrobe section, it forms a protecting cover for the garments suspended from the hangers mounted with said section.

From the foregoing description it will be seen that the curtain and laundry bag is of very simple construction and is well adapted for the purpose described.

What I claim as my invention:

1. The combination with a trunk wardrobe section having an open top and front and a garment hanger track and hangers mounted thereon, said trunk section also having opposite side openings in its upper

rear and lower front portions, of a curtain 65 and laundry bag therefor, comprising a fabric extending over the track and covering the open top and front and having looped upper rear and lower front edge portions 70 the portion of the fabric covering the open 75 front being in the form of a bag having a front opening, means supporting the upper front portion of the fabric, and endwise yieldable bars extending through the looped upper rear and lower front edge portions 75 of the fabric and entering the trunk section opposite side openings for removably connecting the fabric to said trunk section.

2. The combination with a trunk wardrobe section having an open top and front and a garment hanger track and hangers mounted thereon, said trunk section also having opposite side openings, of a curtain and laundry bag therefor, comprising a fabric extending over the track and covering the open top and front and having looped upper and lower edge portions, the portion of the fabric covering the open front being in the form of a bag having a front opening, and bars extending through the looped edge 80 portions of the fabric and entering the trunk section opposite side openings for removably connecting the fabric to said trunk section, said bars having yieldable end extensions 85 which enter some of the opposite 90 side openings.

3. The combination with a trunk wardrobe section having an open top and front and a garment hanger track extension extending transversely of the upper front portion of the trunk section, said trunk section also having garment hangers mounted on the extension track and openings formed in the opposite side portions of said trunk section, of a curtain and laundry bag therefor, 100 comprising a fabric extending over the extension track and covering the open top and front and having looped upper and lower edge portions, the portion of the fabric covering the open front being in the form of a bag having a front opening, and bars extending through the looped edge 105 portions of the fabric and entering the trunk section opposite side openings for removably connecting the fabric to said trunk section, said bars having yieldable end extensions which enter some of the opposite side openings.

4. The combination with a trunk wardrobe section having an open top and front and a garment hanger track extension extending transversely of the upper front portion of the trunk section, said trunk section also having garment hangers mounted on the extension track and openings formed in the opposite side portions of said trunk section, 115 of a curtain and laundry bag therefor, comprising fabric extending over the extension track and covering the open top and front

and having looped upper and lower edge portions, the portion of the fabric covering the open front being in the form of a bag having a front opening, and bars extending through the looped edge portions of the fabric and entering the trunk section opposite side openings for removably connecting the fabric to said trunk section, said bars having extensions on one end which enter some of the opposite side openings, and coiled springs interposed between the extensions and the bars for holding the extensions yieldingly in their outer positions.

In testimony whereof, I affix my signature.

GEORGE HENRY WHEARY.
